CABINET HINGE

Roy A. Stone, Rockford, Ill., assignor to National Lock Company, Rockford, Ill., a corporation of Delaware

Application February 1, 1946, Serial No. 644,713

6 Claims. (Cl. 16—135)

1

This invention relates generally to hinges, and more particularly to hinges suitable for the mounting of hollow metal doors on sheet metal cabinets or the like.

One of the purposes of my present invention is to provide a hinge which will serve, in addition to its hinging function, to reinforce and strengthen the sheet metal door which it supports. With this object in view, the door wing of the hinge is designed to be located within the hollow door where it is concealed from view and serves both as a door support and a door reinforcement.

Another object of my invention is to provide a hinge by which a door may be supported so that no portion of the hinge or the hinged edge of the door will project beyond the plane of the side of the cabinet during any of the opening or closing movements thereof. A cabinet may accordingly be placed in a corner of a room or with its side against a wall, or two cabinets may be abutted together, without interfering with the opening of the doors.

A further advantageous feature is that the hinge also serves as a stop to limit the opening movement of the door and furthermore the abutting surfaces which provide such stop are concealed, thus preventing the chipping or marring of exposed enameled surfaces of the door such as is usually produced by a stop.

Another object is to provide a sheet metal hinge which can be economically shaped and assembled, and attached to the door of a cabinet by permanent spot welding.

Other objects and advantages of my invention should be readily appreciated as the same becomes better understood by reference to the following description when considered in connection with the accompanying drawings.

Referring to the drawings,

Fig. 1 is a fragmental perspective view, with certain parts broken away, of a hinge embodying my invention mounted in a cabinet;

Fig. 2 is a fragmental perspective view of the structure shown in Fig. 1, but viewed from the interior of the cabinet;

Fig. 3 is an elevation of the hinge viewed on the line 3—3 of Fig. 1;

Fig. 4 is an elevation of a hinge viewed from the line 4—4 of Fig. 2;

Fig. 5 is a sectional view on the line 5—5 of Fig. 3;

Fig. 6 is a similar view on the line 6—6 of Fig. 3;

Fig. 7 is a view similar to Fig. 5, illustrating

2

two cabinets disposed in abutting relation without interfering with the opening of the doors;

Fig. 8 is a side elevation of the sheet metal blank from which the door wing of the hinge is formed;

Fig. 9 is an edge view of the blank after being bent as indicated in Fig. 8;

Fig. 10 is a face view of the partially formed blank of Fig. 9 indicating the next step in the formation of the wing;

Fig. 11 is a face view of the partially formed wing indicating the final bending step in the production of the wing; and

Fig. 12 is a front elevation of the completed door wing.

Referring more specifically to the structural details included in the preferred embodiment of the invention disclosed on the drawings, one end wall of a container or cabinet, such as a kitchen cabinet, locker or the like, is designated on the drawings by reference character 13. The wall, as will be obvious, is of sheet metal formation with its margin bent to form a channel-shaped stile 14 presenting a door frame wall 15 upon which the door 16 of sheet metal hollow construction is adapted to be mounted.

While two or more hinges are customarily employed for the mounting of each door, I have herein shown, for illustrative purposes merely, 30 one of such hinges constructed in accordance with my invention. The hinge, generally speaking, is of three-piece construction, comprising a cabinet wing 17, a door wing 18, and a pintle 19 by which said wings are pivotally connected together.

The cabinet wing, which is formed of sheet metal, consists of a base portion 21 adapted to be mounted on the stile 14 by means of a plurality of screws or bolts 22, an outwardly extending arm 23 projecting at an incline from the portion 21, as will be apparent from Fig. 5, and an extension 24 of said arm bent to project therefrom in a plane substantially perpendicular to the plane of the base portion 21. The free margin of the extension 24 is rolled back to form a journal 25 for the pintle 19. The wall 15 of the cabinet is provided with an opening 30 for each cabinet wing.

The door wing is also formed from a single sheet 50 of metal, the fabrication of which into the completed wing will be readily apparent from a consideration of Figs. 8 to 12, inclusive. As shown in Fig. 8, a metal sheet is cut or stamped to form a blank shaped as shown having an elongated central notch 26 along one edge disposed between

Journals 27 and 28, similar to the journal 25 on the cabinet wing and formed by rolling back the metal extensions at each end of the notch 26. This flat blank with the spaced apart pintle journals at one edge thereof is then bent on the line 29 to dispose the margin 31 of the blank carrying the journals at substantially right angles to the original plane of the blank, as exemplified in Fig. 9.

The blank is then bent on the line 32 (Fig. 10) to dispose the main portion of the blank substantially parallel with the wall 31, thus providing a channel-shaped member consisting of the base or bottom wall 33, the marginal wall 31 carrying the journals 27 and 28, and the main body wall extending parallel with the wall 31. The central portions of this body wall are now bent at right angles to the plane of the body on the lines 34 and 35 (Fig. 11) to provide the flanges 36 and 37 projecting outwardly from the attaching portions 38 and 39 remaining in the plane of the original blank. It will be apparent, particularly from Figs. 1 and 4, that the flanges 36 and 37 are respectively notched, as indicated at 41 and 42, to underlie and accommodate the journals 27 and 28, respectively, and that they extend outwardly substantially the depth of the door, that is, from the inner wall 43 to the outer wall 44 thereof, so as to strengthen and reinforce the door and prevent inward bending or collapsing of the outer wall under stress. The reinforcing flanges are spaced apart sufficiently to accommodate between them the projecting arm of the cabinet wing. Similarly, the journals 27 and 28 on the door wing are spaced to accommodate between them the journal 25 of the cabinet wing. When the journals are disposed in alignment, the two wings of the hinge are pivotally connected together by the insertion of the pintle or hinge pin 19 through the journals, as shown.

In practice the hinge is usually assembled and mounted in the door and later mounted on the cabinet. The inner wall 43 of the door is provided with an opening 45 adapted to accommodate the arm 23 of the cabinet wing, as will be apparent from Figs. 2 and 3. The opening is formed by cutting the door wall and bending inwardly the wall material around three sides of which the cuts have been made to thereby form the inwardly projecting flange 46 which, as will be apparent from Fig. 1, extends between the reinforcing flanges 36 and 37 and also extends to the outer wall 44 of the door to further strengthen and rigidify the structure. The transversely extending flanges 36, 37 and 46 surround the hinge opening 45 so as to preclude the insulation or silencing material customarily placed within the door from working out through said hinge opening.

When the hinge has been positioned within the door, as illustrated, with the arm 23 projecting through the opening 45, the door wing is spot welded to the door, particularly along the base wall 33, thereby securely mounting the hinge and at the same time strengthening and reinforcing the door. For the purpose of providing additional strength, the corners of the door wing body may be embossed, as indicated by reference character 47, by a stamping operation which bends the corners inwardly for a limited distance to produce a bracing effect.

After the hinge has been secured in the door, the door may be mounted on the cabinet by simply projecting the base portions 21 of the cabinet wings through the suitably located openings 30 in the cabinet frame and securing the wing to the cabinet stile by means of the screws or bolts 22.

It will be apparent that the axis about which the door will pivot in its opening and closing movements is spaced a substantial distance outwardly from the face of the cabinet. In fact, the pivot pin or pintle is located adjacent to the plane of the outer face of the door. The hinged edge of the door will during the opening and closing movements of the door swing in an arc which never intersects the plane of the side wall of the cabinet. The cabinet may, therefore, be located in a corner of a room close against the wall without interfering with the movements of the door, or two cabinets may be mounted in juxtaposition, as illustrated in Fig. 7, without the adjacent doors interfering with each other during their opening and closing movements.

From Fig. 7 wherein the door of the left-hand cabinet is shown as fully open, it will be manifest that the cabinet wing of the hinge presents a surface in the path of the reinforced wall at the inner side of the hinge opening, which serves as a stop or abutment to limit the extent of the opening movement of the door. The abutting surfaces forming the stop are concealed so that the chipping or marring of an exposed surface of the door by contact with a stop is obviated.

From the foregoing it will be manifest that I have provided a cabinet hinge which can be economically manufactured and easily installed, and which, in addition to its hinge function as a pivotal door support, also serves to strengthen and reinforce the door structure. The hinge is mounted within the door, instead of on the outside, and is therefore not visible, and its pivot pin is so located that a wall or another cabinet abutting the side wall of the cabinet on which the door is mounted in no wise interferes with the opening and closing of the door.

The structural details illustrated and described may be varied within considerable limits without exceeding the scope of the invention as defined in the following claims.

I claim:

1. A cabinet hinge, consisting of a cabinet wing and a door wing pivotally connected together, said cabinet wing being adapted to be anchored at one end on a cabinet frame or the like and to project outwardly therefrom into a hollow metal door, and said cabinet wing being provided at its extremity with a hinge pintle journal, said door wing having connected channel-shaped upper and lower portions, the free edges of one side wall of the channel of each portion being provided with hinge pintle journals, the other side wall of the channel of each portion having a strengthening and door reinforcing flange projecting from the plane of such other side wall toward said one side wall of such portion, the pintle journals of said wings being disposed in longitudinal alignment, and a hinge pin extending through said journals.

2. A cabinet hinge, consisting of pivotally connected cabinet and door wings, the cabinet wing being adapted to be mounted at one end on a cabinet and being provided at its other end with a hinge pintle journal, the door wing being of channel-shaped formation, including a short side wall portion and a pair of long side wall portions, the free edge of the short side wall portion having a pair of spaced apart hinge pin journals, and each of the long wall portions having an integral flange extending at approximately a right angle to the plane of such wall, and a hinge pin extending through all of said journals whereby said wings are connected together.

3. A cabinet hinge, comprising a pair of sheet metal wings pivotally connected together, one of said wings being adapted to be mounted at one end on a cabinet and provided at its other end with a hinge pin journal, the other wing being of channel-shape at one end, each of the channel side walls being divided into two parts connected together at the bottom wall of the channel, the free extremity of each of the said parts of one of said side walls of the channel being provided with a hinge pin journal and each of the other side wall parts of the channel being provided with an integral reinforcing flange disposed at right angles to the plane of its adjacent connected wall part, and a hinge pin extending through said journals whereby said wings are pivotally connected.

4. A cabinet hinge, comprising a pair of wings formed of sheet metal, one wing being adapted to be mounted within a hollow metal door and being of channel-shape, one side wall of the channel having a pair of spaced apart pintle journals with aligned axes, a portion of the metal of the other side wall of the channel extending at right angles to the plane of such side wall and toward the plane of the first side wall thereby to provide a strengthening and reinforcing flange, the other wing consisting of a base portion adapted to be mounted upon the stile of a metal cabinet or the like, an arm projecting from said base portion and an extension of said arm extending at approximately a right angle to the base portion and provided at its extremity with a pintle journal disposed between the pintle journals of said first mentioned wing, and a hinge pin connecting said wings.

5. A cabinet hinge, comprising a pair of pivotally connected sheet metal wings, one of said wings being adapted to be mounted within a hollow metal door, said wing being composed of one piece of sheet metal of channel shape, one side wall of the channel being provided with a pair of spaced apart hinge pin journals and the other side wall being provided with spaced strength-

ening and reinforcing flanges extending at right angles to the plane of the wall in the direction of the first said side wall, the other wing comprising a base portion adapted to be mounted upon the stile of a cabinet or the like, an arm extending therefrom, an extension of said arm being disposed approximately perpendicularly to said base portion and provided at its extremity with a hinge pin journal, a projection of the plane of the base portion intercepting said extension between the last said journal and the juncture of the arm and its extension, and a hinge pin extending through said journals whereby said wings are pivotally connected.

15 6. A cabinet hinge, consisting of a pair of sheet metal wings provided with hinge pin journals and a hinge pin extending through said journals whereby said wings are pivotally connected, one of said wings being of channel-shape, one side wall of said channel having an opening intermediate of the channel ends for passage of a part of the other wing therethrough, said one side wall having strengthening and reinforcing flanges extending from opposite margins defining said opening and toward the opposite side wall of the channel, the other wing comprising a portion adapted to be mounted upon the stile of a cabinet or the like, and an offset arm extending outwardly therefrom through said opening in the said one 20 wing side wall and journaled on said hinge pin connecting said wings.
